(57) **CLAIM**

The ornamental design for an espresso coffee machine as shown and described.

DESCRIPTION

FIG. 1 is a front, left and upper perspective view of an espresso coffee machine showing my new design.

FIG. 2 is a front view thereof;

FIG. 3 is a rear view thereof;

FIG. 4 is a left side view thereof;

FIG. 5 is a right left side view thereof;

FIG. 6 is a top view thereof;

FIG. 7 is a bottom view thereof; and,

FIG. 8 is a rear, right and upper perspective view thereof. The broken lines of FIGS. 2 and 7 illustrate portions of the espresso coffee machine that form no part of the claimed design.
